DESIGN FOR A LETTERING SCRIBER

Francesco G. Collura, New York, N. Y., assignor to
Keuffel & Esser Company, Hoboken, N. J., a
corporation of New Jersey

Application March 26, 1941, Serial No. 99,905

Term of patent 14 years

To all whom it may concern:

Be it known that I, Francesco G. Collura, a citizen of the United States and residing in the city of New York, county of New York, and State of New York, have invented a new, original, and ornamental Design for a Lettering Scriber, of which the following is a specification, reference being had to the accompanying drawing, forming a part thereof.

Figure 1 is a view in perspective of a lettering scriber showing my new design;

Figure 2 is a view in plan;

Figure 3 is a view in side elevation; and,
Figure 4 is an end view.

The marker element illustrated partly in dotted lines and partly in full lines at the left in Fig. 1 has been omitted in Figs. 2, 3, and 4.

I claim:

The ornamental design for a lettering scriber, as shown and described.

FRANCESCO G. COLLURA.
